UNITED STATES PATENT OFFICE.

RALPH ERSKINE ELLIS, OF MUNCIE, INDIANA, ASSIGNOR OF ONE-HALF TO
GEORGE W. CROZIER, OF SAME PLACE.

FOLDING CARRIAGE-TOP.

SPECIFICATION forming part of Letters Patent No. 283,873, dated August 28, 1883.

Application filed July 6, 1883. (No model.)

To all whom it may concern:

Be it known that I, RALPH E. ELLIS, a citizen of the United States, residing at Muncie, in the county of Delaware and State of Indiana, have invented a new and useful Folding Carriage-Top, of which the following is a specification.

My invention relates to improvements in folding carriage-tops; and it consists in dispensing with the front bow used in four-bow tops, making a top with three bows, the front part of which consists of a front section of a bow, four longitudinal slats and three cross-braces, all connected together and curved 15 downward in the shape of a top, the said front part being hinged to the top of the front bow, so that it will fold down on the bows when they are pressed together or laid back.

The object of my invention is to construct a 20 carriage-top the front part of which consists of a slat-frame hinged to the top of the front bow, thereby dispensing with the stuffing of the front and allowing the said front to be folded down on the bows when the top is let 25 down. I attain these objects by the mechanism illustrated by the accompanying drawings, in which—

Figure 1 is a side elevation of a top in use, and Fig. 2 is a view looking down on the front 30 of an uncovered top.

Similar letters refer to similar parts throughout the several views.

The bows A B C and the prop D D' are all old and constructed in the usual manner. 35 The front a' of the top extends over and forward of the bow A. To the top of the bow A are secured the ears c', for the purpose of securing the rod c, which passes through the rear ends of the four curved wooden slats, b, 40 which project forward and join the front section, F, all as shown in Fig. 2.

A cross-bar, b'', (of wood or metal,) is secured across the slats b, near the bow A, as shown, and two cross-bars, b', are secured to the ends of the section F, and across the slats b, near 45 their front ends, all as shown in Fig. 2.

The prop-arms D are secured to the ends of the section at e, and near the top of bow B, so that the front part, a', may be made to stand out in shape, as shown in Fig. 1, or, when the 50 top is layed back, it will fold down over the rear part, which is crimped and compressed down in the usual manner, as shown by dotted lines in Fig. 1, thus presenting a neat and compact appearance.

By dispensing with the front bow of the old-style tops I am enabled to project the front a' farther forward, and have no bow in the way in getting in and out of the buggy. I also dispense with the heavy and irregular stuffing, 60 and the cover will always retain its even convexed shape by reason of the slats and cross-braces all being curved slightly downward, as shown.

I am aware of what has been done by Stead- 65 man and Spar, and

What I claim, and wish to secure by Letters Patent, is—

In a folding carriage-top, the wooden slats b, secured to the section F, and having two 70 cross-braces, b', secured crosswise of the said slats and section, the slats b all secured together by a cross-brace, b'', the whole hinged to the top of the bow A, by a rod, c, passing through the ears c', and the ends of the slats b, 75 all for the purpose set forth.

RALPH ERSKINE ELLIS.
